(57) **CLAIM**

The ornamental design for an expandable wall mount luminaire, as shown and described.

DESCRIPTION

FIG. 1 is a top perspective view of a first embodiment of my design;

FIG. 2 is a bottom perspective view of my design shown in FIG. 1;

FIG. 3 is a top plan view of my design shown in FIG. 1; FIG. 4 is a bottom plan view of my design shown in FIG. 1; FIG. 5 is a front elevational view of my design shown in FIG. 1;

FIG. 6 is a right-side elevational view of my design shown in FIG. 1, the left-side elevational view being the mirror image thereof;

FIG. 7 is a top plan view of a second embodiment of my design;

FIG. 8 is a bottom plan view of my design shown in FIG. 7; FIG. 9 is a front elevational view of my design shown in FIG. 7;

FIG. 10 is a right-side elevational view of my design shown in FIG. 7, the left-side elevational view being the mirror image thereof;

FIG. 11 is a top plan view of a third embodiment of my design;

FIG. 12 is a bottom plan view of my design shown in FIG. 11; FIG. 13 is a front elevational view of my design shown in FIG. 11; and,

FIG. 14 is a right-side elevational view of my design shown in FIG. 11, the left-side elevational view being the mirror image thereof.

Sections of the luminaire in FIGS. 11-13 are shown separated and embraced by a bracket to represent a continuation of the design extending uniformly to any length.
